BY

ATTORNEY

UNITED STATES PATENT OFFICE

2,102,363

BATHING SUIT

Theodore R. Kugler, Inglewood, Calif.

Application August 22, 1932, Serial No. 629,857
Renewed April 15, 1935

8 Claims. (Cl. 2—67)

My invention relates to articles of apparel, and particularly to bathing suits and the like.

When a bather desires to remove his bathing suit and put on his clothing it is necessary that he completely remove his bathing attire before dressing. At most beaches and public bathing places bathers are not allowed to change their clothing in tents, automobiles, etc., but must rent a dressing room.

10 It is an object of my invention to provide a bathing or similar suit which will permit a bather to partially dress and subsequently remove his bathing suit from under his clothing.

15 Further objects and advantages will be made manifest in the following description taken in connection with the accompanying drawing, in which:

Fig. 1 is a perspective view of a preferred embodiment of my invention being worn by a bather.

20 Fig. 2 is a rear view of the bather and suit shown in Fig. 1.

Fig. 3 is an elevational view of the suit shown in Figs. 1 and 2 as it appears when unfastened with the various parts thereof extended.

25 Referring particularly to the drawing, a bathing suit 10, comprising a preferred embodiment of my invention, includes a front or main portion 11. Formed integral with portion 11 is a pair of shoulder straps 12, the free ends of the latter being formed to provide buttonholes 13. Sewed to opposite sides of the portion 11 are suitable buttons 14, as shown in Fig. 3. Formed integral with the front portion 11 and extending outwardly therefrom are hip covering flaps 16. Joined to the front portion 11 by a crotch member 19 is a breech covering 20. Sewed at its top edge to the front portion 11 and at its opposite vertical edges to the hip covering flaps 16 is a conventional skirt 21, a similar skirt 22 being provided in like manner on the breech covering 20.

40 Fixed on opposite vertical edges of the flaps 16 and breech covering 20 as by stitching 24 are slide fasteners 25 comprised of stringers 26 which carry a plurality of interlocking members 27. Slidable on the members 27 are slides 28. The fasteners 25 are common in the art, these being preferably of the type in which the stringers can be completely separated as is disclosed in U. S. Patent No. 1,842,045.

45 To put on the suit 10 of my invention a bather first places the straps 12 over his shoulders, crosses the straps on his back as shown in Fig. 2, and buttons the free ends of the straps onto the buttons 14 as shown in Fig. 1. The breech covering 20 is then drawn rearwardly between the legs,

the member 19 covering the crotch, as shown in Fig. 1. The upper ends of the fasteners 25 are then brought into proper engagement and the slides 28 are drawn downwardly, thus causing the interlocking members 27 to be guided into interlocking engagement in a well known manner.

When the bather desires to remove his bathing suit, he puts on his trousers and shirt, leaving the shirt unbuttoned. Then by pulling the slides 28 upward the members 27 are disengaged freeing the breech covering 20 from the hip flaps 16, thus allowing the covering 20 to be drawn forward between the bather's legs. Then, by unbuttoning the straps 12 from the buttons 14, the entire suit 10 may be removed from the bather, it being clear that the bather's body is substantially covered by his trousers and shirt while the suit 10 is being removed.

It is seen in Figs. 1 and 2 that the suit 10 of my invention is novel in appearance and securely embraces the bather, it being also clear from the foregoing description that the suit 10 can be conveniently removed by the bather in public places without the expense and inconvenience of renting a dressing room.

Although I have shown and described but one form of my invention, it is to be understood that various modifications might be made therein without departing from the scope of the appended claims.

I claim as my invention:

1. In an article of swimming apparel, the combination of: a front body covering; a plurality of straps secured to said front covering, said straps being adapted to embrace the wearer's body; means for removably securing the free ends of said straps to said front covering; hip covering flaps formed on said front covering; a breech covering; a crotch member joining said breech covering with a lower portion of said front covering; and means for attaching or detaching said breech covering to or from said hip covering flaps.

2. In an article of swimming apparel, the combination of: a front body covering; means for removably securing the upper portion of said front covering to the wearer's body; hip covering flaps formed on said front covering; a breech covering; a crotch member joining said breech covering with a lower portion of said front covering; and attaching means provided on opposite vertical edges of said hip covering flaps and said breech covering, said attaching means being adapted to removably secure said breech covering to said hip covering flaps in embracing rela-

tion with the hips and upper portions of the wearer's thighs.

3. In an article of swimming apparel, the combination of: a front body covering; means for removably securing the upper portion of said front covering to the wearer's body; hip covering flaps formed on said front covering; a breech covering; a crotch member joining said breech covering with a lower portion of said front covering; attaching means provided on opposite vertical edges of said hip covering flaps and said breech covering, said attaching means being adapted to removably secure said breech covering to said hip covering flaps in embracing relation with the hips and upper portions of the wearer's thighs; and skirt portions secured to said breech covering and said hip covering flaps.

4. In an article of swimming apparel, the combination of: a front body covering; single fastening means provided on opposite sides of the upper portion of said front covering; a pair of shoulder straps formed with and extending upward from said front covering; means on the free ends of said straps to engage with said fastening means when said straps are disposed in embracing relation with the wearer's body; hip covering flaps formed on the lower portion of said front covering; a breech covering; a crotch member joining said breech covering with a lower portion of said front covering; and means for removably securing vertical edge portions of said breech covering to vertical edge portions of said hip covering flaps.

5. In an article of swimming apparel, the combination of: a pair of bathing trunks; a continuous skirt of substantially the same length as said trunks extending entirely around said trunks, the upper edge of said skirt being secured to the upper edge of said trunks, said trunks and said skirt being parted along a vertical line on the outside of each hip; a plurality of strings of hookless fastening means, each of which strings is permanently attached to one edge of said trunks and an adjacent edge of said skirt along one side of one of said lines; and slide means for causing said hookless fastening means to be temporarily interengaged on said lines to hold said parted edges of said pair of trunks and said skirt together or to separate said hookless fastening means to permit the garment to be removed.

6. In an article of swimming apparel, the combination of: a pair of bathing trunks; a continuous skirt of substantially the same length as said trunks extending entirely around said trunks, the upper edge of said skirt being secured to the upper edge of said trunks, said trunks and said skirt being parted along a vertical line on the outside of each hip; a plurality of strings of hookless fastening means, each of which strings is permanently attached to one edge of said trunks and an adjacent edge of said skirt along one side of one of said lines; slide means for

causing said hookless fastening means to be temporarily interengaged on said lines to hold said parted edges of said pair of trunks and said skirt together or to separate said hookless fastening means to permit the garment to be removed; a front body covering provided on said trunks and extending upwardly therefrom, said front body covering having shoulder straps provided integrally thereon, said shoulder straps having buttonholes provided in their ends; and buttons along the sides of said front body covering over which said buttonholes may be placed after said straps have been extended up over the shoulders and across the back of the wearer.

7. In a pair of bathing trunks extending from the waist line down to the crotch and adapted for removal from underneath a pair of trousers without removing said trousers, the combination of: a front area covering section having free lateral edges; a breech covering section having free lateral edges; means permanently connecting the aforesaid sections to form a narrow crotch covering section adapted to normally lie between the legs; a plurality of separate strings of complementary hookless metal fastening means, each of said strings being permanently secured to one of said sections along one of the free lateral edges thereof; and runner means by which said fastening means of adjacent free lateral edges of said sections may be initially joined and then formed into unbroken metal seams by simple straight movements of said runner means extending the entire length of said strings, said metal seams being capable of being entirely disconnected by a reverse operation of said runner means beneath said trousers.

8. In a pair of bathing trunks extending from the waist line down to the crotch and adapted for removal from underneath a pair of trousers without removing said trousers, the combination of: a front area covering section having free lateral edges; a breech covering section having free lateral edges; means permanently connecting the aforesaid sections to form a narrow crotch covering section adapted to normally lie between the legs; a plurality of separate strings of complementary hookless metal fastening means, each of said strings being permanently secured to one of said sections along one of the free lateral edges thereof; and runner means by which said fastening means of adjacent free lateral edges of said sections may be initially joined and then formed into unbroken metal seams by simple straight movements of said runner means extending the entire length of said strings, said metal seams being capable of being entirely disconnected by a reverse operation of said runner means beneath said trousers, said sections being substantially equal in width so as to cause said metal seams to overlie the extreme lateral portions of the hips.

THEODORE R. KUGLER.
